UNITED STATES PATENT OFFICE.

GUY P. THURBER, OF PITTSBURGH, PENNSYLVANIA.

TRAIN-CONTROL SYSTEM.

1,204,717.

Specification of Letters Patent. Patented Nov. 14, 1916.

Application filed March 12, 1913. Serial No. 753,705.

To all whom it may concern:

Be it known that I, GUY P. THURBER, a citizen of the United States, and resident of Pittsburgh, in the county of Allegheny and

5 State of Pennsylvania, have invented certain new and useful Improvements in Train- Control Systems, of which the following is a specification.

10 The present invention relates to train control systems, and has for its main object the prevention of the operation of the train controlling means when the speed of the train falls below a certain rate.

15 Accordingly one feature of the invention consists in a system having a normally closed train controlling circuit normally completed through the traffic track, together with track means for preventing the passage of the current of the train circuit through 20 the track, means on the train permitting the completion of the train controlling circuit without passing through the track normally inoperative, and automatic means controlled by the speed of the train for rendering said 25 inoperative means operative when the speed of the train falls below a certain rate.

30 The train controlling circuit may be of any character and may be used for any purpose, such as, for the giving of a signal, but 35 in its preferred form it exercises a control over suitable train controlling means.

35 The precise nature of the train controlling means will of course vary, depending upon whether steam or electricity is employed as 40 a motive power, but as here shown, the train controlling means are suitably connected to the air brake system. In its preferred form the train controlling circuit is normally closed and normally holds the train controlling means inoperative, and suitable track 45 means are employed for rupturing said train controlling circuit.

45 Preferably an electro-magnetic device is utilized to hold the train controlling circuit closed, and this train controlling circuit may be one circuit or a plurality of circuits.

50 A shunt is usually provided by which the train circuit may be restored temporarily or whereby the electro-magnetic device is reenergized. In addition to this I provide a shunt for preventing the deenergization of the train controlling circuit by providing a shunt whereby the train circuit may be completed without passing through the 55 track. This shunt is under the control of the speed of the train, in such a way that

the shunt is automatically closed when the speed of the train falls below a certain rate—thus rendering the train controlling means inoperative.

60

The train preferably establishes connection with the traffic track by means of the two contacts, here the wheels or trucks of the train, and suitable insulation is provided whereby the train controlling circuit is normally forced through the track from one contact to the other.

65

Other features will appear as the specification proceeds.

70 In the drawings the invention is shown in several concrete and preferred forms, but changes of construction may be made without departing from the scope of the invention.

75 In the said drawings: Figure 1 is a diagrammatic view of a train control system showing a preferred form of the invention. Fig. 2 is a perspective view of a fluid-operated speed controlled element, with parts in section and removed. Fig. 3 shows a perspective view of a ball governor operated speed controlled element, with parts in section. Fig. 4 is a perspective view, largely diagrammatic, of a generator and solenoid speed controlled element.

80

85 Similar characters of reference indicate corresponding parts in the several views.

1 indicates a traffic track and 2 is the train, which may be one or more cars, represented by trucks 3 and 4 forming contacts 90 electrically connecting the train with the track.

95 A primary circuit forming part of the train controlling circuit is provided composed of the conductor 5, armature 6, conductor 7, electro-magnetic device or relay 8, conductor 9 passing through insulation 10, battery or source of energy 11, conductor 12, conductor 13, truck 3, track 1, and truck 4. Suitable means for rupturing this circuit 10 are provided consisting of the track insulation 14, and a jumper circuit 15, with armature 16 and relay 17, forms a path around the insulation 14. When the jumper circuit is broken, the continuity of the train controlling circuit is ruptured and the relay 8 is deenergized. Under the control of the primary circuit is a subsidiary circuit as follows: from battery 18, conductor 19, armature 20, conductor 21, magnet valve 22, 11 conductor 23, armature 24, conductors 25 and 26.

Obviously when the relay 8 is deenergized not only will the armature 6 drop, but the armatures 20 and 24 will likewise drop, thus deenergizing the magnet valve 22. The 5 magnet valve 22 controls the brake valve 27 which controls the escape of fluid under pressure from the train line 28. When the magnet valve 22 is energized the brake valve 27 is held closed or inoperative, and when the 10 magnet valve is deenergized the brake valve is opened. A supplementary circuit is also fed by the battery 18 as follows: through conductor 29, switch 30, conductor 31, light 32 and conductor 33.

15 A shunt is provided whereby the train controlling circuit may be restored and the relay 8 energized temporarily as follows: conductor 34, switch 35, conductor 35^a, relay 8, conductor 9 and battery 11. Another shunt 20 is provided whereby the deenergization of the relay 8 may be prevented if the train is running below a certain rate of speed as follows: from battery 11, conductor 9, relay 8, conductor 35^a, conductor 36, contact 37, 25 contact member 38, contact 39, conductor 40, circuit closer 41, conductor 42 and conductor 12 to battery 11.

30 The contact member 38 is normally so positioned as not to engage with the contacts 37 and 39, but upon the slowing down of the speed of the train, the contact member 38 will bridge the space between the contacts 37 and 39 and automatically complete the shunt, which is in effect a shunt around the 35 insulations 10 and 14, permitting the train controlling circuit to be completed without passing through the track.

35 In the form shown in Fig. 2, 43 is a piston, moving in the chamber or cylinder 44, provided with a stem 45 carrying the contact member 38 and insulated portion 46. Springs 47 and 48 of substantially equal strength engage either side of the piston 43 and tend to keep the latter in a central position. 48^a and 49 are two intermeshing gears which rotate in the chamber 50 below the cylinder 44, and which, while free to rotate, fit rather snugly in the said chamber 50. These gears are driven from an axle 51 of the train by means of spur gears 52, 53, and 45 stub shaft 54, so as to rotate in accordance with the speed of the train. A passage 55 extends from the cylinder 44 at one side of the piston 43 to the chamber 50 at a point intermediate the gears 48^a and 49 on one side of the same. Another passage 56 extends from the cylinder 44 on the other side of the piston 43 to the chamber 50 at a point intermediate the gears 48^a and 49 on the other side of the same. Passages 57 extend through the piston 43 from one side to the other, of less capacity than the passages 55 and 56. Assume now that the chamber 50 and the cylinder 44 are filled with oil, the 50 rotation of the gears 48^a and 49, in either di-

rection, will establish a circulation of the oil through the passages 55, 56 and 57, chamber 50 and cylinder 44, the space between the teeth of the gears and casing of the chamber 50 acting to hold the oil to convey the same. 70 Owing to the fact, however, that the passages 57 have less capacity than the passages 55 and 56, a choking effect will be established, if the gears 48^a and 49 rotate at a considerable speed, and the piston 43 will be 75 moved either up or down thereby bringing the contact member 38 out of engagement with the contacts 37 and 39, thereby breaking the shunt represented by the conductors 36 and 40. If the speed of the train now 80 decreases, the choking effect will cease or be diminished and the piston 43 will move to its central position whereby the contact member 38 will complete the shunt by engaging the contacts 37 and 39. By varying the 85 relation between the size of the passages 55, 56 and 57, the speed at which the shunt will be closed can be regulated.

In Fig. 3, the contact member 38 is in the form of a ring and is mounted on a sleeve 90 58 provided with insulation 59. This sleeve 58 is slidingly and rotatably mounted on the upright shaft 60, which is driven by means of bevel gears 61 and 62 from the axle 51 of the train. Carried by this sleeve 58 and 95 by the collar 63 which is pinned to the shaft 60 at 66 are pivoted arms 64 and ball governors 65. Interposed between the sleeve 58 and collar 63 is a spring 67 which normally tends to move the sleeve 58 downward so 10 that the contact member 38 will engage with the contacts 37 and 39. At high speed the ball governors 65 will move outwardly and raise the sleeve 58 until the shunt is broken, while at low speed the governors 65 will 15 move inwardly and the shunt will be reestablished.

In Fig. 4, the contact member 38 is a pivoted armature controlled by the solenoid 68. The latter is energized from the shunt 11 wound generator 69 by means of conductors 70 and 71. The generator 69 is driven from the axle 51 of the train by means of gears 72 and 73. When the train is moving at high speed the current generated by 69 will energize the solenoid 68 and the plunger 74 will move upwardly thus breaking the shunt. When the generator 69 is rotated slowly, gravity will move the plunger 74 downward thus establishing the shunt. 12

What is claimed, is:

1. A system of train control comprising: a traffic track, a train, train controlling means, a normally closed circuit normally holding said train controlling means against operation, means including a circuit normally completed through said traffic track for holding said train controlling circuit closed, and manually operable means for maintaining said circuit closing means in 13

circuit closing condition regardless of the condition of said track circuit.

2. A system of train control comprising: a traffic track, a train, train controlling means, a normally closed circuit normally holding said train controlling means against operation, means including a circuit normally completed through said traffic track for holding said train controlling circuit closed, and means under the control of the engineer for maintaining said circuit closing means in circuit closing condition regardless of the condition of said track circuit.

15 3. A system of train control comprising: a traffic track, a train, train controlling means, a normally closed circuit normally holding said train controlling means against operation, means including a circuit normally completed through said traffic track for holding said train controlling circuit closed, and means controlled by the speed of the train including a manually operable means for maintaining said circuit closer 20 in circuit closing condition regardless of the condition of said track circuit.

4. A system of train control comprising: a traffic track, a train, train controlling means, a normally closed circuit normally holding said train controlling means against operation, means including a circuit normally completed through said traffic track for holding said train controlling circuit closed, means controlled by the speed of 35 the train including a manually operable means for maintaining said circuit closer in circuit closing condition regardless of the condition of the track circuit, and means for maintaining said circuit closer in circuit closing condition regardless of the speed of the train and of the condition of said track circuit.

40 5. A system of train control comprising: a traffic track, a train, train controlling devices, a normally closed train controlling

circuit, normally completed through the track, normally holding said train controlling means inoperative, track means for rupturing said train controlling circuit, means controlled by the speed of the train 50 for automatically permitting said train circuit to be completed without passing through the track when the speed of the train falls below a certain rate, and means for completing said train circuit without 55 passing through the track and regardless of the speed of the train.

6. A system of train control comprising: a traffic track, a train, train controlling means, a normally closed train controlling 60 circuit normally completed through the track for holding said train controlling means inoperative, track means for interrupting said train controlling circuit, and means controlled by the speed of the train 65 including a manually operable circuit closer for placing said train circuit in condition to be completed without passing through the track when the speed of the train falls below a certain rate.

7. A system of train control comprising: a traffic track, a train, a train controlling circuit normally completed through the traffic track, a source of energy in said circuit, an electro-magnetic device for normally 75 holding said train circuit closed, means for deenergizing said electro-magnetic device, and means controlled by the speed of the train and including a manually operable circuit closer whereby the deenergization of 80 the electro-magnetic device may be prevented when the speed of the train falls below a certain rate.

Signed at Pittsburgh, in the county of Allegheny and State of Pennsylvania, this 85 10th day of March, A. D. 1913.
